United States Patent

Des. 235,188
Patented May 27, 1975

235,188

WRENCH

Franz Palfi, 122 West St., Battle Creek, Mich. 49017

Filed July 2, 1973, Ser. No. 375,627

Term of patent 14 years

Int. Cl. D8—05

U.S. Cl. D8—29

FIG. 1 is a side elevational view of a wrench according to the present invention.

FIG. 2 is an end view taken at the right-hand side of FIG. 1.

FIG. 3 is a view looking at the top of the wrench in the position shown in FIG. 1.

FIG. 4 is a view looking at the bottom of the wrench in the position shown in FIG. 1, and

FIG. 5 is a cross-sectional view taken at the line 5—5 of FIG. 1, looking in the direction of the arrows.

I claim:

The ornamental design of a wrench, substantially as shown.
